DESIGN FOR A WASHABLE TOY BLOCK OR SIMILAR ARTICLE

Benjamin Greenfield, New York, N. Y.

Application February 14, 1945, Serial No. 117,933

Term of patent 7 years

(Cl. D34—15)

To all whom it may concern:

Be it known that I, Benjamin Greenfield, a citizen of the United States of America, residing in New York city, county of New York and State of New York, have invented a new, original, and ornamental Design for a Washable Toy Block or Similar Article, of which the following is a specification, reference being had to the accompanying drawing, forming part thereof, wherein,

Figure 1 is a front elevational view of a washable toy block or similar article showing my new design.

Figure 2 is a right side elevational view.

Figure 3 is a top plan view thereof.

The rear, left side and bottom views are substantially the same in appearance as their corresponding sides shown.

I claim:

The ornamental design for a washable toy block or similar article, substantially as shown and described.

BENJAMIN GREENFIELD.
